CLAIM

U.S. PATENT DOCUMENTS

The ornamental design for a clamp meter, as shown and described.

D440,892 S * 4/2001 Kuramoto D10/79
D467,190 S * 12/2002 Ikeda et al. D10/79
D472,830 S * 4/2003 Chang D10/79
D514,005 S * 1/2006 Gregorec et al. D10/79
D545,704 S * 7/2007 Kuramoto D10/79
D567,687 S * 4/2008 Elrod D10/79

DESCRIPTION

FOREIGN PATENT DOCUMENTS

FIG. 1 is a front view of a clamp meter.

JP D1270415 S 3/2006
JP D1302738 S 4/2007
JP D1303574 S 5/2007
TW 453800 9/2001

FIG. 2 is a back view thereof.

FIG. 3 is a right side view thereof.

FIG. 4 is a left side view thereof.

FIG. 5 is a top view thereof.

FIG. 6 is a bottom view thereof; and,

FIG. 7 is a perspective view thereof.

The broken lines form no part of the claimed design.
